UNITED STATES PATENT OFFICE.

WILLIAM F. BOSSERT, OF UTICA, NEW YORK.

RAILWAY-BUFFER.

No. 844,092.

Specification of Letters Patent.

Patented Feb. 12, 1907.

Application filed October 23, 1906. Serial No. 340,230.

To all whom it may concern:

Be it known that I, WILLIAM F. BOSSERT, a citizen of the United States, residing at Utica, in the county of Oneida and State of New York, have invented certain new and useful Improvements in Railway-Buffers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in railway buffers or bumping-posts; and the object in view is to provide a simple and efficient device of this nature for use at railway-terminals for the purpose of reducing to a minimum the damage to rolling-stock due to the jarring of cars.

The invention consists, further, in the provision of apparatus whereby the initial power of a moving car or cars may be utilized to operate a powerful brake directly connected with the bumping-post, so as to bring the cars to a standstill gradually without sudden jar or jolt, so damaging to railway property.

The invention consists, further, in the provision of means in connection with a buffer or bumping-post whereby cars may be prevented from leaving a track while being stopped. Heretofore with the buffers commonly used no provision whatever has been made to guard against this contingency, and it is a well-known fact that in the stopping of cars the impact of the moving car against an unyielding bumping-post or buffer has a tendency to make the car slide upward and jump the bumping-post, thereby endangering life and property.

The present invention comprises various details of construction and combinations and arrangements of parts, which will be herein-after fully described and then specifically defined in the appended claims.

I illustrate my invention in the accompanying drawings, in which—

Figure 1 is a horizontal longitudinal section through my invention. Fig. 2 is a side elevation. Fig. 3 is a sectional view taken on line 3 3 of Fig. 1. Fig. 4 is a front elevation. Fig. 5 is a rear elevation, and Fig. 6 is a detail perspective view of two of the friction clamping-jaws forming a part of the invention.

Reference now being had to the details of the drawings by letter, A designates a frame made of any suitable metal and having a cylindrical aperture A' formed therein longitudinally with the track, and B designates a cap closing one end of said cylindrical opening. C designates a hollow piston or buffer mounted to have a longitudinal movement within said aperture or opening in the frame and is provided with a recessed head C', the recess in which is adapted to receive a coupling-head upon a car, the walls to the recess being tapered in order to guide the coupling-head therein. D designates a spiral spring inserted within the aperture or opening in said frame and also within the hollow portion of said buffer or piston, and E designates a second or auxiliary spiral spring also mounted within the hollow portion of the buffer or piston, the outer ends of said springs bearing against the head of the buffer or piston, as shown clearly in Fig. 1 of the drawings, while their inner ends are designed to bear yieldingly against the cap R. F and F' are friction-claws mounted in a transverse opening at right angles to the opening in which said piston or buffer is adapted to have a play, and G G designate two springs, the inner ends of which are adapted to bear against the outer faces of said jaws F and F', respectively, while their outer ends bear against the cam-actuated plates H, one mounted adjacent to each end of the transverse opening through the casing. Auxiliary spiral springs I also bear between the clamping-jaws F and F' and said plates H, thereby holding the jaws yieldingly against the hollow shank portion of said buffer or piston. The adjacent edges of said jaws are provided with serrations J, (shown clearly in Fig. 6,) which intermesh with one another and adapted to guide the jaws to and from each other. Projecting from the opposite edges of the casing or frame A are the arms O, carrying the fulcrum-pins O', upon which the cams P are eccentrically mounted. It will be noted that the outer face of each of said plates H is concaved and is adapted to receive the curved edge of one of said cam members, it also being noted that the pivotal pins O' are mounted at one side of the longitudinal center of the transverse opening in which said friction-jaws are mounted for the purpose of allowing the springs G and I to react against the cams P and links Q, which connect the cams with the fulcrum-pins Q', carried by

the head of said buffer or piston, thereby assisting the springs D and E to return the former to their original positions after the stoppage of cars and removal therefrom, 5 adapted to adjust the apparatus for the next operation.

R R designate pivot-pins mounted upon the frame A, upon the forward end thereof, and to which are pivotally connected the 10 stay-rods R', which in turn are pivotally connected to the pins S upon the cross-rail S', and the latter are held to the track by means of nuts and bolts S⁴. Said cross-piece S' is provided with apertures S⁵ near its 15 center, through which the arms of the U-shaped rod T are adapted to pass, which U-shaped rod also extends through openings in the tie and passes underneath an I-beam U. Nuts T², mounted upon the threaded ends of 20 said rod T, serve to securely hold the cross-piece and tie to said reinforcing I-beam, thereby affording secure anchorage for fastening the bumping-post or buffer direct to the track without the need of excavations for 25 foundations.

The frame A is also provided on its under side with means to receive an I-beam L, (shown in Fig. 2 of the drawings,) the lower end of which beam L bears against a plate L', 30 fastened to the tie, while its upper end contacts with the under surface of the frame at the proper height between the surface of the track and coupler.

To the rear of the frame are socket members A³, adapted to receive the corresponding 35 ends of the braces A⁴, which are fastened to the track-rails by means of the specially-designed blocks A⁵, which partially embrace the rails and are fastened to the same by means 40 of bolts. In order to provide against the spreading of the rails by heavy pressure or jar, the two blocks A' are connected together by a heavy bar A⁶. (Shown clearly in Fig. 5 of the drawings.)

45 In operation it will be noted that cars approaching and coming in contact with the recessed heads of the buffers or pistons will first have to overcome the resistance of the powerful springs inserted within the frame 50 in alinement with the buffer or piston, and afterward the immense friction between the jaws F and F', which are caused to be thrown against the circumference of the piston or buffer by the action of the cam forcing the plates H against the coiled springs G and I, 55 which in turn bear against said jaws as the impact of a coupler comes in contact with the piston-head. By this arrangement of apparatus it is apparent that the initial 60 power or momentum of moving cars is greatly dissipated by the tremendous friction through the cams P upon the springs, which in turn bear against the jaws, causing the same to bind against the circumference of 65 the piston or buffer. It will also be noted

that the greater the impact against the buffer-head the greater will be the friction between the jaws and the circumference of the hollow portion of the buffer or piston, thereby avoiding all sudden jar to the apparatus and also to the cars and avoiding a common tendency for lifting cars from the track as they come against an unyielding contact-surface.

What I claim is—

1. A railway-buffer comprising a movable, spring-actuated hollow piston provided with a head, clamping-jaws adapted to contact with the circumference of the piston, and means actuated by the head of the piston to 80 cause said clamping-jaws to frictionally engage the piston, as set forth. 75

2. A railway-buffer comprising a frame, a piston mounted in an opening in said frame, jaws having a movement at right angles to 85 the length of said piston and adapted to frictionally contact with the outer circumference thereof, cams having pivotal connection with a head or shoulder of said piston, and springs interposed between said cams 90 and jaws, as set forth.

3. A railway-buffer comprising a frame, a hollow piston mounted in an opening therein, friction-jaws mounted in an opening at right angles to the opening in which said piston is 95 mounted, springs interposed between the outer faces of said jaws and the head of said piston, cams pivotally mounted upon the frame, springs interposed between said cams and said jaws, and link connections between 100 said cams and head of the piston, as set forth.

4. A railway-buffer comprising a frame, a hollow piston mounted in an opening therein, friction-jaws mounted in an opening at right 105 angles to the opening in which said piston is mounted, springs interposed between the outer faces of said jaws and the head of said piston, cams pivotally mounted upon the frame, plates mounted in openings at right 110 angles to the opening in which said piston is mounted and against which said cams are adapted to frictionally contact, springs interposed between said plates and said jaws, and link connections between said cams and the 115 head of said piston, as set forth.

5. A railway-buffer comprising a frame having openings at right angles to each other formed therein, a hollow piston mounted in one of said openings and provided with a head, one face of which is recessed and adapted to receive the impact of a coupler-head, interlocking jaws mounted in the other opening and adapted to contact with the circumference of said hollow piston, 120 cams mounted upon the frame, plates mounted in the openings in which said jaws have play, springs interposed between said jaws and cams, links pivotally connecting said cams and the head of said piston, and springs 125 130

interposed between the jaws and the head of said piston, as set forth.

6. A railway-buffer comprising a frame having openings at right angles to each other formed therein, a hollow piston mounted in one of said openings and provided with a head, one face of which is recessed and adapted to receive the impact of a coupler-head, interlocking jaws mounted in the other opening and adapted to contact with the circumference of said hollow piston, cams mounted upon the frame, plates mounted in the openings in which said jaws have play, springs interposed between said jaws and cams, links pivotally connecting said cams and the head of said piston, a closure to one end of the opening in which said piston is mounted, springs interposed between said closure and piston-head and springs interposed between the opposite sides of the jaws and the piston-head, as set forth.

7. A railway-buffer comprising a frame having openings at right angles to each other formed therein, a piston mounted in one of said openings and provided with a head with a recessed face, friction-jaws mounted in the opening at right angles to the opening in which said piston is mounted, plates mounted in the opening in which said jaws have play, springs interposed between said plates and jaws and between the latter and the head of the piston, cams, pivot-pins mounted at one side of the center of the opening in which said jaws are mounted and upon which said cams are pivotally mounted, the latter being adapted to bear against the concaved surfaces of said plates, and links connecting said cams with the head of the piston, as set forth.

8. A railway-buffer comprising a casing, a spring-pressed piston mounted therein, clamping-jaws, means for throwing said jaws into contact with the circumference of the piston when the same is moved longitudinally, brace-bars pivotally connected at corresponding ends to said frame and connected to the rails of a railway at their opposite ends, and a cross-piece connecting said brace-bars, as set forth.

9. A railway-buffer comprising a casing, a spring-pressed piston mounted therein, clamping-jaws, means for throwing said jaws into contact with the circumference of the piston when the same is moved longitudinally, brace-bars pivotally connected at corresponding ends to said frame, a cross-

piece pivoted to the outer ends of said brace-bars, means for fastening said cross-piece to the rails of a railway, a U-shaped rod passing through apertures in said cross-piece, an I-beam underneath the ties of a railway and underneath which said U-shaped rod passes, and nuts mounted upon the threaded end of the latter and adapted to bear against said cross-piece, as set forth. 65

10. A railway-buffer comprising a casing, a spring-pressed piston mounted therein, clamping-jaws, means for throwing said jaws into contact with the circumference of the piston when the same is moved longitudinally, brace-bars pivotally connected at corresponding ends to said frame, a cross-piece pivoted to the outer ends of said brace-bars, means for fastening said cross-piece to the rails of a railway, a U-shaped rod passing through apertures in said cross-piece, an I-beam underneath the ties of a railway and underneath which said U-shaped rod passes, nuts mounted upon the threaded end of the latter and adapted to bear against said cross-piece, bars engaging socket members in said frame at their inner ends, and blocks fastened to the railway-rail to which the outer ends of said bars engaging the sockets of the frame, are held, as set forth. 70 75 80

11. A railway-buffer comprising a casing, a spring-pressed piston mounted therein, clamping-jaws, means for throwing said jaws into contact with the circumference of the piston when the same is moved longitudinally, brace-bars pivotally connected at corresponding ends to said frame, a cross-piece pivoted to the outer ends of said brace-bars, means for fastening said cross-piece to the rails of a railway, a U-shaped rod passing through apertures in said cross-piece, an I-beam underneath the ties of a railway and underneath which said U-shaped rod passes, nuts mounted upon the threaded end of the latter and adapted to bear against said cross-piece, bars engaging socket members in said frame at their inner ends, blocks fastened to the railway-rail to which the outer ends of said bars engaging the sockets of the frame, are held, and an I-beam supporting said frame, as set forth. 85 90 95 100 105

In testimony whereof I hereunto affix my signature in the presence of two witnesses.
